UNITED STATES PATENT OFFICE.

JOHN A. WILLIAMS, OF BROOKLYN, NEW YORK, ASSIGNOR TO UNITED STATES SLOT MACHINE COMPANY, OF NEW YORK, N. Y., A CORPORATION OF NEW YORK.

VENDING APPARATUS.

No. 826,207.

Specification of Letters Patent.

Patented July 17, 1906.

Application filed November 29, 1902. Serial No. 133,281.

To all whom it may concern:

Be it known that I, JOHN A. WILLIAMS, a citizen of the United States, residing at Brooklyn, in the county of Kings and State 5 of New York, have invented certain new and useful Improvements in Vending Apparatus, of which the following is a specification.

My present invention pertains to improvements in vending apparatus, and relates 10 more particularly to the means employed for holding the operative mechanisms or parts in their proper relations, all of which will be hereinafter more fully described, reference being had to the annexed drawings, where- 15 in—

Figure 1 is a perspective view of a cabinet or case with the front or closure thereof removed, it being seen from the rear; Fig. 2, a front elevation of the same, the operative 20 mechanism and magazine being removed at the right-hand side of said figure; Fig. 3, a vertical sectional view on the line 1 1 of Fig. 2; Fig. 4, a perspective view of the lower portion of the casing, the parts being shown on a 25 scale somewhat enlarged; and Fig. 5 a perspective view of a portion of the plate or member which is secured to the lower end of the door or closure.

One object of my invention is to provide a 30 ready means for securing the magazine which holds the goods in position, so that it will maintain its proper place with relation to the other parts of the device.

A further object is to provide means for se- 35 curing the operative mechanism within the casing, so that it may be readily removed and replaced when necessary.

Another object of the invention is to so 40 protect the lower end of the removable door or closure that any tampering with or breaking into the apparatus is practically pre- cluded.

A still further object of the invention is to 45 provide a device which will insure the proper delivery of the goods into the way or channel which passes to the outside of the casing.

Referring to the drawings, A indicates the 50 frame or casing, which in the form illustrated is rectangular in shape and is provided with a removable door or closure B.

C C indicate the delivery mechanisms, they being shown simply in outline in the present application. The operative portions

of said delivery mechanisms are mounted or secured upon a plate D, the upper end of 55 which is engaged by a lip E on a plate F, which is secured to the side wall of the casing. At the junction of the base G and each side wall there is secured an angle-plate H, screws or similar fastening devices passing 60 through said plate into both the base and the side walls. The upper edge of said plate is provided with a lip I, which, as does also the lip E, stands away from the side wall. These lips engage the upper and lower ends of the 65 plate D, which carries the operative mechanism, as above stated, so that when the mechanism is shoved back into place it is securely held by said lips. The same construction is employed upon both sides of the casing 70 where what is known as a "double" machine is used, and it will of course be understood that but one delivery mechanism may be employed, if so desired.

Secured to the base of the casing and ex- 75 tends backward against the rear wall thereof is a delivery chute or channel J, the side walls K of which project upwardly beneath the downwardly-extending plates L of the delivery mechanisms. The side walls or plates 80 K are provided with laterally-extending wings M at their lower ends, the purpose of which will presently appear.

A plate N forms an extension of the chute or channel J, said plate projecting through an 85 opening O, formed in the lower portion of the door or closure for the delivery of the goods. The outer end of the plate N is formed with a ridge or shoulder P, which affords an abut- 90 ment or stop for the goods as they are deliv- ered.

Where two delivery mechanisms are em- 95 ployed, there is pivotally suspended above the delivery chute or channel intermediate the mechanisms a valve or deflector Q, which in the form illustrated is simply a sheet-metal plate suspended from the rear of the casing by a bolt or pin R. When a package of goods is thrown toward the delivery chute or channel by one of the delivery mechanisms, it will 100 come in contact with the pivoted plate or deflector Q, and as a consequence be somewhat retarded in its movement. The plate will also prevent the goods from being thrown over into the opposite delivery mechanism 105 and will likewise cause the goods to pass

down into the chute or channel without turning or twisting around. This latter function of the plate prevents the goods from cramping or binding in the chute or channel.

5 In the form illustrated the delivery mechanism is provided at its upper end with cross-bars S, which engage the opposite faces of the lower end of the goods-holding magazine T. The magazine is of the form now usually employed in connection with machines of this general class. One face thereof is provided with a notch U, through which passes one arm of a spring-plate V, said plate or spring being secured to the under face of the top of 10 the casing in line with the upper end of the magazine. As will be noted, each end of the spring-plate is provided with two downwardly-projecting lugs or fingers W and X, the finger X projecting downwardly to a greater extent than the finger W. When the magazines are removed, the free arms will assume the positions shown at the right-hand side of Fig. 2, and when the magazines are in place the position of the parts will be that indicated at the left of Fig. 2 and also in Fig. 1, wherein it will be noted that the upper edge of the magazine is engaged by or held between the ends of the downwardly-projecting fingers W and X.

30 When it is desired to remove a magazine, all that is necessary to be done is to press the outer end of the spring-plate upwardly, thereby disengaging the upper end of the magazine from said spring-plate, after which the 35 magazine may be tilted toward the center of the casing and withdrawn from engagement with the cross-bars or other holding devices which are attached to the operative mechanism.

40 In replacing the magazine the lower end thereof is passed in between the bars S, the notched upper end being brought into alignment with the spring-plate V, after which it is moved along the spring-plate until the 45 magazine passes over the short finger W and abuts against the longer finger X. Said longer finger X prevents the overthrow of the magazine toward the side of the casing. In other words, it forms a stop or abutment, preventing further movement of the magazine. 50 The spring construction not only affords a ready means for the removal and insertion of the magazine, but it likewise at all times keeps the magazine down to its proper position upon the operative mechanism.

55 Machines of this character are of course subjected to varying climatic conditions, and the casings will consequently shrink and swell to a certain extent. If the upper end 60 of the magazine be attached directly to the casing and the operative mechanism at a point below, there may be a separation of the magazine and the operative mechanism or a binding between the parts, according as the 65 casing shrinks or elongates under varying

weather conditions. The present construction obviates both of these difficulties, and the lower end of the magazine is held at all times in its proper position with relation to the operative-mechanism.

70 As before stated, the lower edge of the door or closure B is provided with an opening O, which comes in alignment with the delivery chute or channel. It is likewise provided with a second opening a, which extends practically across the entire width of the door, said opening being formed in alignment with the actuating portions of the delivery mechanisms so as to expose the cranks or handles b and the coin slots or openings c.

80 In order to protect the lower end of the door and to prevent access to the money-drawers of the machine and the operative portions of the mechanisms, said lower end is sheathed or protected by a plate d. This plate is secured to the inner lower face of the door, being cut away where the opening O is formed, and likewise provided with a recessed or depressed section e. (Best shown in Fig. 5.) The lower end of the plate is turned outwardly at right angles to the top portion thereof and then upwardly, as best illustrated in Figs. 1 and 5. This formation of the lower end produces a channel which when the parts are assembled embraces the 90 lower end of the door or closure B, the face thereof being cut away so that the upwardly-projecting end f lies flush, or practically so, with the forward or outer face of the door or closure. Openings g are formed in the lower 95 edge of the plate in line with lugs or fingers h, which are turned upwardly from the lower member of the angle-plates H.

100 A metallic cross-bar i, the lower end of which is seated in the depression e in the 105 plate d, extends from said plate across the opening a. Both ends of the cross-bar are securely fixed in position, and it will be seen that the cross-bar bridges over the space between the front plates of the operative mechanisms, closing the forward portion of the chute or channel through which the goods are delivered.

110 When the door is put in place, the lugs or fingers h pass into the openings g, the door 115 being swung in at the upper end and secured by a lock j, carried by the said upper end.

To facilitate the positioning of the door and the entrance of the lugs or fingers h into the 120 openings g, I provide two conical-shaped projections, which are so situated upon the base as to properly guide the lower end of the door toward the lugs as the door is put in place. With the door of the casing thus formed and protected it has been found by actual use of 125 the machines that any tampering with the same is practically precluded. It is apparently well-nigh impossible by any ordinary means to force the door or to cut away the lower portion thereof to such an extent as would 130

permit the withdrawal of deposited coins or goods from the mechanism. The wings M, which extend in behind the plate d, prevent the coin from being withdrawn from the pan, 5 into which it drops from the operative mechanism. While the parts at this point are designed and do in use come so close together as practically to preclude the insertion of any device for withdrawing the coin, still the 10 wings afford a further protection against tampering with the receipts of the machine. By the employment of the angle-plates H, which connect the sides and the base, these parts are secured together in a substantial manner. 15 The angle-plates are supplemental, of course, to the ordinary construction which is employed in making up casings of the kind herein shown and described.

Having thus described my invention, what 20 I claim is—

1. In combination with a suitable casing; operative mechanism carried thereby for the delivery of goods; a goods-magazine; connections intermediate the goods-magazine and 25 the operative mechanism, for holding the lower end of the magazine in proper position; and a spring secured in the upper end of the casing, said spring having downward y-projecting fingers engaging the upper end of the 30 magazine when the magazine is brought to position, substantially as described.

2. In combination with a casing; operative mechanism carried thereby for the delivery of goods; a goods-magazine; means carried by 35 the operative mechanism for positioning the lower end of the magazine with relation to the operative mechanism; a spring secured within the upper end of the casing; and fingers W and X extending downwardly from 40 said spring and embracing the upper end of the magazine when said magazine is brought to its proper position over the operative mechanism, substantially as described.

3. In combination with a suitable casing; 45 a goods-delivery channel mounted centrally thereof; operative mechanisms carried by the casing upon opposite sides of said channel for delivering goods to said channel; a goods-magazine for each of said operative mechanisms; and a spring secured in the upper end 50 of the casing, the free ends of said spring engaging and retaining the upper ends of the magazines when they are brought into proper position, substantially as described.

5. In combination with a suitable casing; a delivery-channel or way carried thereby; operative mechanisms also carried by the casing upon opposite sides of the channel, said mechanisms being adapted and arranged 60 to deliver goods to the channel; and means, working in conjunction with said way or channel, for preventing the overthrow of the goods as they are delivered from one or the other of said mechanisms, substantially as 65 described.

5. In combination with a suitable casing; a delivery way or channel carried thereby; operative mechanisms also carried by the casing upon opposite sides of the way or channel and arranged to deliver goods to 70 said channel; and a pivoted valve or deflector mounted above said way or channel, substantially as and for the purpose described.

6. In combination with a suitable casing; operative mechanism for the delivery of 75 goods; a plate D secured to said operative mechanism; a plate F secured to the side wall of the casing and provided with a lip or flange E; an angle-plate H secured to the side of the casing and to the base thereof at 80 their point of junction; and a lip I formed upon the upper edge of the angle-plate, substantially as described.

7. In combination with a suitable casing; operative mechanism carried thereby for the 85 delivery of goods; a door or closure for said casing; a protecting-plate for the lower end of said door, said plate extending around the lower edge of the door and embracing the same; and means for securing the door in 90 position, substantially as described.

8. In combination with a suitable casing; operative mechanism carried thereby for the delivery of goods; a door or closure; a plate d secured upon the rear face of said door and embracing the lower edge thereof, said plate having recesses formed in the lower edge of the same; lugs h extending upwardly from the base, arranged to enter said recesses in 95 the plate; and means for securing the upper 100 end of the door in position.

9. In combination with a suitable casing; operative mechanism carried thereby for the delivery of goods; angle-plates secured to the side walls of the casing and the base 105 thereof at their points of junction, the upper edge of each plate engaging and serving, in part, to hold the operative mechanism in position; lugs h extending upwardly from said angle-plates; a door or closure for said casing; 110 and a plate secured to the rear face of the door, said plate embracing the lower edge of the door and formed with openings or recesses to receive the lugs when the door is in position, substantially as described. 115

10. In combination with a suitable casing; a delivery-channel carried thereby; goods-delivery mechanisms also carried by the casing upon opposite sides of the channel; a door or closure for said casing; a plate d secured 120 to the rear face of the door, said plate embracing the lower end of said door; a cross-bar or plate i extending from the plate d across an opening formed in the door above said plate and covering the space between 125 the goods-delivering mechanisms; and means for securing said door in position.

11. In combination with a suitable casing; a goods-delivery channel mounted centrally thereof at the lower end of the casing; the 130

4
side walls of the channel being provided with laterally-extending wings *M*; goods-delivery mechanisms carried by the casing upon opposite sides of said channel; a door or closure 5 for said casing; a plate *d* secured to the rear face of said door at the lower end thereof, said plate having openings *g* formed therein; a cross-bar *i* extending from said plate *d* upwardly across an opening *a* formed in the 10 door said plate likewise covering the space between the goods-delivery mechanisms and closing the upper portion of the delivery-

channel; lugs *h* extending upwardly from the base of the casing and entering the openings *g* when the door is in position; and 15 means for securing the upper end of said door in place.

In testimony whereof I have signed my name to this specification in the presence of two subscribing witnesses.

JOHN A. WILLIAMS.
